UNITED STATES PATENT OFFICE.

GUSTAVUS E. STRAUSS, OF NEW YORK, N. Y., AND EMIL KLAHN, OF WEST HOBOKEN, NEW JERSEY.

NUT-LOCK.

SPECIFICATION forming part of Letters Patent No. 578,276, dated March 2, 1897.

Application filed June 27, 1896. Serial No. 597,242. (No model.)

To all whom it may concern:

Be it known that we, GUSTAVUS E. STRAUSS, of New York, in the county of New York and State of New York, and EMIL KLAHN, of West Hoboken, in the county of Hudson and State of New Jersey, citizens of the United States, have invented certain new and useful Improvements in Nut-Locks, of which the following is a specification.

10 This invention relates to improvements in nut-locks, and has for its purpose to provide a screw-nut which, when screwed upon a screw-bolt, cannot be loosened by the vibration of the machine or other object to which 15 it is applied. This is attained by the construction shown in the accompanying drawings, in which—

Figure 1 is a longitudinal section of our improved screw-nut and fastening attachment 20 and of a screw-bolt to which the same is attached, and Fig. 2 is a section on line 2 2 of Fig. 1. Fig. 3 is a top view, and Fig. 4 a section, of the screw-nut. Fig. 5 represents a detail showing the fastening attachment.

25 Similar letters of reference indicate corresponding parts.

A in the drawings is a screw-nut, which on its top is provided with a tapering inwardly-expanding circular excavation *a*, the side wall 30 of which is ribbed or serrated.

B is an annular or nearly annular ring, which has an inwardly-extending projection *b* and is split, so as to leave in its body an opening. The corners *b' b'* of the open ring 35 are made sharp, which may be obtained by flattening the outer end portions of the same, as shown in Fig. 5. The ring is made of spring-acting metal, so that the ends of the same can be pressed together, and the outer 40 periphery of the same may be beveled, so as to correspond with the taper of the excavation *a* of the screw-nut.

D represents a screw-bolt which has a longitudinal groove *d*.

45 Our improved screw-nut is used in the following manner: After the screw-nut is screwed upon the screw-bolt and has on the same obtained the required position the ends of the open ring B are pressed together, so 50 that the circumference of the same is decreased, and the ring is then placed into the excavation *a* of the screw-nut and pushed

down upon the bottom of the same. In doing so the projection *b* of the ring slides in the groove *d* of the screw-bolt. As soon as 55 the ring has been placed into the excavation of the screw-nut, as said before, the ends of the ring, by the spring action of the same, will spread apart and the sharp corners of the ring will enter between the ribs or serrations 60 of the excavation, so that thereby, and by the projection *b*, located in the groove *d* of the bolt, a lateral as well as an upward motion of the ring is prevented. It is then entirely impossible for the screw-nut to get loose on the 65 screw-bolt by vibration or any other cause, nor can it be detached from the same.

Having thus described our invention, we claim as new and desire to secure by Letters Patent—

1. A screw-nut having on its top an inwardly-tapering excavation provided with lateral ribs or serrations and an open spring-acting ring having its outer periphery beveled to correspond with the taper of the excavation and placed into the latter, the corners of the ring engaging the ribs or serrations of the 70 excavation, substantially as set forth.

2. A screw-nut having on its top an excavation and a spring-acting open ring placed 80 into the excavation and being provided with an inwardly-extending projection, in combination with a screw-bolt having a longitudinal groove, the said projection of the open ring extending into the said groove of the 85 screw-bolt, substantially as set forth.

3. A screw-nut having on its top an excavation provided with lateral ribs or serrations and an open spring-acting ring provided with an inwardly-extending projection the ends of 90 the ring engaging the ribs or serrations of the said excavation, in combination with a screw-bolt having a longitudinal groove in which the projection of the said ring is located, substantially as and for the purpose set forth. 95

Signed at New York, in the county and State of New York, this 26th day of June, A. D. 1896.

GUSTAVUS E. STRAUSS.
EMIL KLAHN.
